UNITED STATES PATENT OFFICE.

EDWARD H. TATE, OF MALDEN, MASSACHUSETTS, ASSIGNOR TO TATE MANUFACTURING COMPANY, OF BOSTON, MASSACHUSETTS, A CORPORATION OF MASSACHUSETTS.

MOP.

1,097,892.

Specification of Letters Patent.

Patented May 26, 1914.

Application filed March 6, 1913. Serial No. 752,311.

To all whom it may concern:

Be it known that I, EDWARD H. TATE, a citizen of the United States, and a resident of Malden, in the county of Middlesex and State of Massachusetts, have invented certain new and useful Improvements in Mops, of which the following is a specification.

This invention relates to a mop, the head of which is composed of a tubular body 10 usually composed of textile fabric, and strands usually composed of filaments of textile material twisted together, the strands projecting from one side of the body and forming the acting portion of the mop. A 15 mop of this character is provided with a head-supporting member usually composed of a piece of wire passed through the tubular body and bent to give the mop head the desired form, and a handle suitably connected with the holding member.

The invention has for its object to provide an improved construction of the holding member and of the means employed for connecting the handle therewith, in such manner that the holding member and the handle-connecting means may be quickly and conveniently separated to permit the cleansing and removal of the mop head, and assembled to provide an operative mop which may be 30 used either in a dry or a wet condition and employed to clean floors, walls, etc.

The invention consists in the improvements which I will now proceed to describe and claim.

35 Of the accompanying drawings:—Figure 1 represents a plan view of a mop embodying my invention. Fig. 2 represents a section on line 2—2 of Fig. 1. Figs. 3 and 4 represent perspective views of the members 40 of the clamp hereinafter described. Fig. 5 represents a section on line 5—5 of Fig. 1.

The same reference characters indicate the same parts in all the figures.

In the drawings:—12 represents the body 45 portion and 13 the fibrous acting portion of the mop, the body portion being preferably composed of strips of fabric placed on opposite sides of an assemblage of fibrous threads and stitched through and through to 50 form the tubular body, from one side of which the threads project. The tubular body is open from end to end so that the wire-holding member hereinafter described may be inserted in it, the holder extending 55 through the tubular body and confining it

in curved form as indicated by Fig. 1. The said holding member is composed of a single piece of stout wire comprising a curved portion 14, located mainly within the body portion 12, and two substantially straight shanks 15 formed by bending the end portions of the wire outwardly at an obtuse angle to the extremities of the curved portion 14, said shanks projecting outwardly from the curved portion between the ends of 60 the body 12 and being adapted to be engaged by the clamp next described. Said clamp in the embodiment of my invention here shown comprises a base member 16 and a top member 28 opposed thereto, each of 65 these members being preferably made as a single casting of malleable iron. The base member has substantially flat sides, the upper side 17 constituting a longitudinal seat for the shanks 15. At opposite edges of this 70 seat are outwardly projecting flanges 18 constituting transverse stops to prevent outward displacement of the shanks 15, which are laid upon the seat 17 between said stops. One end of the base member 16 is provided 75 with a transverse rib 19 which projects above the seat 17 and is separated from the flanges 18 by portions 17^a of the seat 17. The rib 19 constitutes a transverse stop adapted to prevent endwise displacement of 80 the shanks 15, the extremities of the curved portion 14 bearing on the rib 19, as indicated by Fig. 1.

The top clamp member 28 is formed to bear on the shanks 15 and hold the same 85 firmly against the seat 17 and stops 18, said top member being pressed toward the base member by a thumb nut 20, engaging a screw 21 passing through orifices 22, 23, in the two members. The under side of the top 90 member 28 is preferably provided with beveled faces 24, Fig. 5, formed to press the shanks 15 outwardly against the stops 18. To increase the strength of the clamp I provide one end of the top member 28 with an 95 offset hook 29 adapted to pass through an orifice 25 in the base member and bear on the under side of the rib 19, as shown by Fig. 2, so that there is a secure connection between the two members which prevents 100 liability of breakage of the top member 28 by the pressure of the shanks 15 against it when the mop is in use.

One of the members of the clamp, preferably the base member, is provided with 110

handle-engaging means, preferably a socket 26 formed integral with the base member and provided with an internal screw thread 27 adapted to engage an external thread 5 on the handle. The socket 26 is preferably disposed at an angle to the base member 16 as shown by Figs. 2 and 3.

It will be seen that the described parts may be conveniently and quickly assembled 10 by placing the shanks 15 on the seat 17, inserting the hook 29 in the orifice 25, inserting the screw 21 in the orifices 22 and 23 and applying the nut 20. The removal of the nut permits the quick separation of the 15 parts.

What I claim and desire to secure by Letters Patent is:—

An improvement in mops comprising a supporting wire adapted to be passed 20 through a tubular mop body and having

bent ends forming shanks, a clamp base member having its upper surface provided with a seat for said shanks and stops for preventing lateral displacement of said shanks, one end of said base member being 25 provided with a transverse rib projecting above said seat and forming a stop to prevent endwise displacement of said shanks, a top clamp member having a hook portion engaging said rib, and means for locking 30 said clamp members together, said upper clamp member having its underside provided with beveled faces acting to press said shanks against said lateral stops.

In testimony whereof I have affixed my 35 signature, in presence of two witnesses.

EDWARD H. TATE.
